UNITED STATES PATENT OFFICE.

NOAH SHAW, OF EAU CLAIRE, WISCONSIN.

DESIGN FOR A CAM.

SPECIFICATION forming part of Design No. 30,101, dated January 31, 1899.

Application filed January 5, 1899. Serial No. 701,268. Term of patent 7 years.

To all whom it may concern:

Be it known that I, NOAH SHAW, a citizen of the United States, residing at Eau Claire, in the county of Eau Claire and State of Wisconsin, have invented and produced a new and original Design for a Cam, of which the following is a specification.

This invention relates to a new and original design for a cam; and it has for its object to provide a design of this character that shall be both useful and ornamental.

The leading feature of the design resides in a flat body of a tapering width and provided at opposite sides of its axial center with duplicate bearing surfaces or edges of equal curvature and having a uniformal convergence in one direction.

While the essential feature of the design resides in the opposite duplicate bearing-surfaces having an equal curvature and a uniform convergence in one direction, it is to be noted that a minor feature of the design is the body, provided at its upper corners with oppositely-located rounded lobes and between said lobes at the top edge with a rounded convexity.

Another minor feature of the design is the circular opening at the axial center of the cam-body.

In the drawings, Figure 1 is a perspective view of the cam embodying the herein-described design. Fig. 2 is a side elevation thereof.

Referring to the drawings, the numeral 1 designates the flat body of the cam, which is 35 of a tapering width. The said tapering flat body is provided at its axial center with a circular opening 2 and at opposite sides of this opening with duplicate bearing surfaces or edges 3 of equal curvature and having a uniformal convergence in one direction. At the upper opposite corners of the cam-body the curved bearing surfaces or edges 3 thereof merge into the oppositely-located rounded lobes 4, between which lobes the body is provided at its top edge with a rounded convexity 5, and while it has already been stated that the essential feature consists in the body having duplicate bearing surfaces or edges converging in one direction it will be observed that these bearing surfaces or edges converge to a point 6, which is located diametrically opposite the rounded convexity 5 at the top edge of the body.

What is claimed is—

The design for a cam, herein shown and described.

In testimony that I claim the foregoing as my own I have hereto affixed my signature in the presence of two witnesses.

NOAH SHAW.
